UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

AUTOMATIC SELECTOR-SWITCH.

1,196,482.

Specification of Letters Patent. Patented Aug. 29, 1916.

Application filed January 3, 1916. Serial No. 69,940.

To all whom it may concern:

Be it known that I, JOHN NEWBERRY REYNOLDS, a citizen of the United States, residing at Greenwich, in the county of Fairfield and State of Connecticut, have invented certain new and useful Improvements in Automatic Selector-Switches, of which the following is a full, clear, concise, and exact description.

- 10 This invention relates to automatic selector switches of the type shown, for example, in United States Patent No. 1,123,696 of January 5, 1915, wherein the terminals are assembled in a large flat-faced bank or 15 panel, over the face of which brush carriers are driven by a continuously moving member, to which they are coupled by idler rollers operated by electromagnets. In switches of this character wherein the brush rods are positively restored upon the dis-establishment of the connection, it is necessary to provide a continuously moving member separate from the member used to drive the carrier during the setting operation.
- 20 25 It is the object of this invention to provide an arrangement wherein the brushes are driven in both directions by a single continuously moving member.

In accordance with this invention, an electromagnet is provided which controls an idler roller adapted, when the armature of such magnet is attracted, to force the brush carrier into engagement with a continuously moving member to drive such carrier in one 35 direction, a second electromagnet being provided with an idler roller adapted, when the armature of such magnet is attracted, to engage both the continuously moving member and the brush carrier, whereby, due to the 40 intermediation of such idler roller, the brush carrier is driven in the opposite direction.

Referring to the drawings, Figure 1 is a side elevation, partially in section, of a switch structure embodying this invention;

45 Fig. 2 is a section on line 2--2 of Fig. 1.

The terminal bank 10 may be of the type disclosed in United States Patent No. 1,127,741 of February 9, 1915, and the brush rods 11, one only of which is shown, may be 50 of the type shown in United States Patent No. 1,123,696 of January 5, 1915 and need not therefore be described in detail herein. The brush shaft 11 carries, at its lower end, a flat metal strip 13. Extending at right angles to the strip 13 is a continuously mov-

ing shaft 50 carrying a cylindrical member 14 coated with cork 15 or other friction material. The strip 13 is adapted to be pressed into engagement with the member 14 by an idler roller 16 carried upon an arm 17, pivoted upon a pin 20, supported in the frame plates 21, 22, which frame plates are secured to the frame 23 of the switch. The motion of armature 24 of magnet 19 is transmitted to arm 17 by a spring 25 secured at one end to said armature and at the other to the end of said arm. Brush rod 11 is arrested upon the selected terminals by deenergizing magnet 19, and is maintained elevated by a pawl 25, which is pivoted upon a pin 26 mounted in the frame plates 21, 22, this pawl entering perforations in strip 13. The return of the brush rod 11 is effected by energizing magnet 27, the armature 28 of which withdraws pawl 25 from engagement with the perforation in strip 13 and presses the cork-coated idler 29 into engagement with the constantly rotating member 14 and the strip 13. The shaft 14, acting through the idler 29, consequently 80 drives the brush rod 11 downwardly. The circuit of magnet 27 is opened in any suitable manner when the brush rod reaches its normal position, whereupon spring 46 retracts the same. The brush-tripping mechanism is shown in detail in Patent 1,123,696 referred to, and need not be described in detail herein, it being sufficient to say that after the brush rod 11 has been elevated a predetermined distance, the magnet 31 is energized, which twists a rod 32, so that a finger 33 carried thereby is placed in alignment with the lever 34 of the particular set 90 of brushes it is desired to trip. Upon further elevation of the brush rod, the lever 34 is depressed by the finger 33, whereupon the member 35, carried by such lever, is moved inwardly to allow the brushes 36, 37, 38 and 39 to engage the terminals 40, 41 and 42. The spring 48 is provided for the purpose 100 of allowing the idler roller 29 to adjust itself to any irregularities in the surface of the continuously moving member 14. It will be noted that the armature 24 and arm 17 are pivoted upon the same pin, and that 105 normally the spring 25 maintains projections 44 on the armature in engagement with the arm 17. As a result of this construction, although the magnet 19 when energized holds the armature 24 against the pole-pieces 110

of said magnet and through the spring 25 carries the arm 17 with it, it will be evident that the idler 16 can move backwardly against the tension of the spring 25 when 5 necessary.

What is claimed is:

1. In an automatic switch, the combination with a row of terminals, a brush carrier having brushes adapted to traverse the 10 same, a continuously moving member, an idler roller and electromagnetic means adapted to actuate the same to force said carrier into engagement with said member to drive said carrier in one direction, of a 15 second idler roller in operative relation to said member and carrier, and electromagnetic means for causing the same to transmit motion from said member to said carrier to drive the same in the opposite direction.
2. In an automatic switch, the combination with a row of terminals, a brush carrier having brushes adapted to traverse the 20 same, a continuously moving member, an idler roller and electromagnetic means adapted to actuate the same to force said 25 carrier into engagement with said member to drive said carrier in one direction, of a second idler roller, and electromagnetic

means adapted to cause the same to engage said member and carrier to drive said carrier in the opposite direction. 30

3. In an automatic switch, the combination with a row of terminals, a continuously moving member, an idler, a brush carrier between said member and idler and an electromagnetic adapted to cause the idler to force said carrier into engagement with said member, of a second idler in operative relation to said member and brush carrier, and an electromagnetic adapted to force said idler 40 into contact with said member and carrier. 35

4. In an automatic switch, a brush carrier and a rotatable member, electromagnetic means adapted to force said carrier into engagement with said member to drive said 45 carrier in one direction, an idler roller in operative relation to the member and carrier, and electromagnetic means for causing the same to transmit motion from said member to said carrier to drive the same in the opposite direction. 50

In witness whereof, I hereunto subscribe my name this 30th day of December A. D., 1915.

JOHN NEWBERRY REYNOLDS.
